PRINTING AND EJECTING MECHANISM FOR
CASH REGISTERSFriedrich W. F. Berger, Berlin, Germany, assignor
to The National Cash Register Company,
Dayton, Ohio, a corporation of MarylandApplication March 7, 1934, Serial No. 714,478
In Germany March 13, 1933

10 Claims. (Cl. 101—287)

This invention relates to improvements in the type of cash register often referred to as an accounting machine or posting machine and illustrated and described in Letters Patent of the 5 United States No. 1,747,397, issued February 18, 1930, to B. M. Shipley.

Generally speaking, it is an object of this invention to provide an accounting machine with means to positively eject record material, said 10 ejecting means also serving as a means for locating record material in relation to the printing mechanism.

A more specific object is to provide the machine of this invention with a reciprocating 15 ejecting bar that extends the full width of the type carriers and impression mechanism and travels across the printing point to positively remove insertable slips from between the type carriers and the impression mechanism.

20 Another object is to supply novel means to align the edge of the insertable slip with the locating ejecting member.

With these and incidental objects in view, the 25 invention consists of certain novel features of construction and combinations of parts, the essential elements of which are set forth in appended claims and a preferred form or embodiment of which is hereinafter described with reference to the drawing which accompanies and 30 forms a part of this specification.

Of said drawing:

Fig. 1 is a front elevation showing the mechanism of this invention.

35 Fig. 2 is a plan view as observed from above illustrating a portion of the impression and ejecting mechanisms.

General description

40 The impression hammer of the instant machine is actuated twice in each machine operation to first print various amounts and data upon an insertable record slip and then to duplicate this impression upon an audit strip which is retained in the machine. The web of the audit 45 strip is unwound from the receiving roll and threaded around various guide rolls past the platen of the impression hammer, thence around the impression hammer, after which it is wound upon a receiving roll in the well known manner. A reversible inking ribbon passes between the 50 web of the audit strip and the type carriers.

Prior to releasing the machine for operation, 55 the record slip is inserted between the inking ribbon and the web of the audit strip, which it

will be recalled are interposed between the impression hammer and the type carriers. During machine operation initial movement of the impression hammer forces the record slip and the inking ribbon into contact with the type carriers to cause an impression to be made on said record slip. Immediately thereafter the record slip is ejected from the machine and the second movement of the impression hammer moves the audit strip into contact with the inking ribbon and the type carriers to cause a duplicate impression to be made upon said audit strip.

The usual slip ejecting mechanism consists of pairs of superimposed rollers or disks between which at the proper time the slip is gripped after which rotation of the rollers ejects the slip. With this type of ejecting mechanism the accidental or intentional insertion of a slip which covers the printing point but which is not wide enough to engage the ejecting rolls, would, upon machine 10 operation, result in such a slip not being ejected after the first impression. Consequently the second impression would also be made upon the record slip thereby preventing a record of the transaction being imprinted upon the audit strip. 15 It is very necessary that a duplicate record of all transactions be kept upon the audit strip, as this record is very important to the proprietor of a business establishment in checking the business over a certain period.

In order to prevent unscrupulous employees from inserting narrow strips of paper between the type carriers and the impression mechanism, thereby destroying the proprietor's record, the instant novel ejecting mechanism was devised. This mechanism consists of a reciprocating bar which passes between the impression hammers and the type carriers immediately after the first impression is made, and positively removes or 20 ejects any material, regardless of size, away from the printing point. This insures a recording of the transaction on the audit strip. The mechanism of this invention will now be described in detail.

Detailed description

Calling attention to Figs. 1 and 2, transversing the machine from front to rear and journaled in a bracket secured to the machine base and the printer front and back frames is a printer 25 shaft 30 having secured thereon a cam 31 with a cam groove 32. Cooperating with the cam groove 32 is a roller 33 carried by a bell crank 34 loose on a rod 35 and connected by a link 36 to an arm 37 secured on a shaft 38, the forward 30

end of which is journaled in a printer front plate 40.

Secured on opposite ends of the shaft 38 are arms 41 and 42 having pivoted thereto, respectively, the left ends of symmetrical links 43 and 44. The right hand ends of the links 43 and 44, respectively, fit loosely on studs 45 and 46 secured in upturned ears 47 and 48 of a slip locating and ejecting bar 49. The ears 47 and 48 of the bar 49 have in the inner surfaces thereof, parallel grooves 50 and 51, which cooperate respectively with parallel rails 52 and 53 formed respectively on stationary and similar plates 39 and 54.

15 Pivoted at 55 is an impression hammer 56 with a platen 57 which is adapted to be rocked clockwise into contact with type carriers 58 loose on a rod 59 supported by the printer frames. Extending above the type carriers 58 is a slip table 60 having an opening 61 through which the impression hammer 56 passes to contact the type carriers 58. The impression hammer 56 is enclosed by a case 62, the right hand end of which is narrowed down and in cooperation with the slip table 60 forms a slip chute 63 for guiding record material between the impression means and the type carriers. The printing on an audit strip 64 is visible through a glass window 65 in the case 62.

30 From the supply roll the web of the audit strip 64 is threaded around the pivot point 55, thence around the guide roll 66 across the face of the platen 57, around a guide roll 67, around the edge of a writing table 68 secured to the impression hammer 56 and then wound upon a receiving roll (not shown). Opposite ends of the guide roll 66 are journaled in arms 69 and 70 secured on a shaft 71 rotatably supported by the plates 39 and 54. An extension 72 of the arm 70 is bent at right-angles to cooperate with a flat spring 73 secured to the impression hammer 56. The spring 73 urges the arm 70 clockwise, as viewed in Fig. 1, into engagement with a stop stud 74 secured in the impression hammer 56. The arm 70 by means of the shaft 71 and the arm 69, urges the roller 66 clockwise, causing said roller and the audit strip 64 to yieldingly engage the upper edge of the ejecting bar 49. An inking ribbon 75 passes around a guide roller 76, thence 45 above the type carriers 58, and around a spring member 77 secured to a guide plate 78. The spring member 77 together with the ink ribbon 75 yieldingly engages the lower edge of the ejecting bar 49.

50 In use, the record slip is inserted within the chute 63 and advanced until the edge thereof, guided by the roller 66 and the spring member 77 engages a V-shaped groove 79 in the right hand edge of the ejecting bar 49. This locates the record slip in relation to the printing mechanism. The first movement of the impression hammer 56 forces the record slip, together with the ink ribbon 75, into contact with the type carriers 58 to impress a record on said slip.

55 Immediately after this first impression is taken the groove 32 in the cam 31 in cooperation with the roller 33 rocks the bell crank 34, first in a clockwise direction, which by means of the link 36 also rocks the arm 37, the shaft 38, and the arms 41 and 42 in a clockwise direction. Clockwise movement of the arms 41 and 42 by means of the links 43 and 44 moves the ejecting bar 49 horizontally toward the right, in which movement it is guided by means of the rails 52 and 70 53, in cooperation with the parallel slots in the

upturned ears of said ejecting bar 49. This initial movement of the ejecting bar 49 positively ejects any record material, regardless of its length, from between the impression hammer 56 and the type carriers 58.

5 Before the second impression is made the cam 31 returns the ejecting bar 49 to normal position, as shown in Fig. 1. Immediately thereafter the impression hammer 56 is again moved downwardly to carry the audit strip 64 and the ink ribbon 75 into contact with the type carriers 58 to print a duplicate record upon said audit strip 64.

The upper end of the extension 72 of the arm 70 forms a convenient fingerpiece 80 by which 15 the shaft 71 and the guide roller 66 may be rocked counterclockwise if necessary to assist in properly inserting and locating record material within the machine.

20 While the forms of mechanisms herein shown and described are admirably adapted to fulfill the objects primarily stated, it is to be understood that it is not intended to confine the invention to the forms of embodiment herein disclosed, for it is susceptible of embodiment in various forms all coming within the scope of the claims which follow.

25 What is claimed is:

1. In a machine of the class described having a plurality of type carriers and an impression hammer cooperating therewith to make imprints upon an insertable record slip, the combination of a bar mounted to reciprocate between the type carriers and the impression hammer; a groove in one edge of the bar to receive the insertable 35 slip; and means including a yieldingly supported roller and a spring cooperating with opposite sides respectively of the bar to guide the insertable slip into the groove to insure proper location and ejection of said slip. 40

2. In a machine of the class described, the combination with type carriers and impression means cooperating with the type carriers to print on insertable record material, of means including a reciprocable member extending the full width of 45 the type carriers and the impression means, and movable therebetween to positively eject the record material inserted between the type carriers and the impression means.

3. In a machine of the class described, having 50 type carriers and impression means cooperable therewith to print on inserted record material, the combination of a member extending across said type carriers and mounted to reciprocate between said type carriers and the impression 55 means, a groove in one edge of the member to receive the record material, resilient means co-extensive with and cooperating with the member to direct record material into the groove, and means to reciprocate the member whereby the 60 inserted record material will always be ejected.

4. In a machine of the class described, having type carriers and impression means cooperating with the type carriers to print on inserted record material, the combination of a member coextensive with said type carriers and impression means and slidably therebetween, a groove in the member to receive the edge of the record material, yieldable means extending along and cooperating with the under side of the member to assist in 70 guiding the record material into the groove, means extending along and resiliently held in engagement with the upper side of the member to also assist in guiding the record material into the groove, said guide means being operable to 75

guide the record material into the groove independently of the width of the material, and means for imparting reciprocating movement to the member to positively eject the inserted record material irrespective of its width.

5. In a machine of the class described, having type carriers and impression means cooperable with said type carriers in each machine operation to print successively upon a plurality of record materials, one superimposed upon another, the combination of a reciprocable member coextensive with the type carriers and impression means, a groove in said member for receiving the edge of one of said record materials, resilient means located adjacent the member to guide the edge of said one record material into the groove, and means to move the member between the type carriers and the impression means to eject said one record material after it has been printed and irrespective of its width whereby the succeeding impression will always be made on the other record material.

6. In a machine of the class described, having type carriers and impression means cooperating with the type carriers to make an impression on an inserted slip and then on an audit strip during each machine operation, the combination of a member extending the full width of the type carrier and impression means, means for supporting the member for reciprocation between the type carriers and impression means, and means for reciprocating said member after the impression means has operated to make an impression on the inserted slip whereby the slip is ejected and the audit strip is left free to receive its impression.

7. In a machine of the class described, having type carriers, impression means cooperable with said type carriers to print on superimposed record materials, said impression means being operable a plurality of times during each machine operation to print on each of the record materials, and means to guide one of said record materials between the type carriers and the impression means, the combination of a member substantially wider than the type carriers and the impression means, means supporting the member for horizontal movement between the type carriers and impression means, a groove in said member adapted throughout its length to receive the edge of another of said record materials, and means to operate the member after the first operation of the impression means whereby the said other record material is ejected irrespective of the width of this record material, and the impression means can thereafter always make a record on the said one record material.

8. In a machine of the class described, having type carriers, impression means cooperating with

said type carriers to print on insertable record material, and means to guide the insertable record material between the type carriers and impression means, the combination of a member extending across the type carriers and impression means and adapted when the machine is at rest to form a locating stop for the record material, guiding means coextensive with the member and cooperable therewith to guide the insertable material into engagement with the member irrespective of the width of the record material, and means to actuate the member during a machine operation to always eject the record material irrespective of its width.

9. In a machine of the class described having type carriers and an impression hammer cooperable with the type carriers to print on an audit strip and an inserted record slip, the combination of means including a resiliently mounted roller for guiding the audit strip relatively to the impression hammer and type carriers, means including a resilient guide member for guiding an ink ribbon between the type carriers and impression hammer, a bar reciprocable between the type carriers and the impression hammer, a groove in said bar for receiving the edge of the inserted record strip, said audit strip guide roller and ink ribbon guide member cooperating with said bar to also guide the inserted slip into said groove to insure the proper location of said slip, and means to impart invariable reciprocating movement to the bar on each machine operation to always eject the slip irrespective of its width.

10. In a machine of the class described, having type carriers and impression means cooperable with the type carriers to successively print on an inserted record slip and an audit strip; the combination of a member extending across the width of the type carriers and the impression means; means for guiding the audit strip relatively to the impression means and the type carriers, said guide means including a resiliently mounted roller coextensive with and cooperable with said member; means to guide an ink ribbon relatively to said type carriers and impression means, said ink ribbon guide means including a resilient plate coextensive with and cooperable with said member; a groove in said member; said resiliently mounted roller together with its audit strip and said resilient plate together with its ink ribbon being effective to guide the inserted slip into the groove irrespective of the width of the slip; and means for operating the member after an impression has been made on the slip whereby the slip is invariably ejected and the succeeding operation of the impression means is effective to print on the audit strip.

FRIEDRICH W. F. BERGER.
